UNITED STATES PATENT OFFICE.

DAVID D. NEVINS, OF ATTLEBOROUGH, ASSIGNOR TO FRANCIS S. BAILEY,
OF NORTH ATTLEBOROUGH, MASSACHUSETTS.

DESIGN FOR AN ORNAMENTAL CHAIN.

SPECIFICATION forming part of Design No. 12,433, dated August 23, 1881.

Application filed January 6, 1881. Term of patent 14 years.

To all whom it may concern:

Be it known that I, DAVID D. NEVINS, of Attleborough, in the county of Bristol and State of Massachusetts, have invented a new and useful Design for Ornamental Chains; and I do hereby declare that the following specification, taken in connection with the accompanying drawings, forming a part of the same, is a full, clear, and exact description thereof.

10 My design relates to an ornamental chain composed of links bent or shaped in a peculiar form, and united in the manner described and shown.

15 Referring to the drawings, Figures 1 and 2 represent a portion of a chain, the views being at right angles to each other; and Fig. 3 shows a single link.

20 The central portion of each link is in the form of the letter U, and from this central portion the 25 arms of the link turn outward in semicircular form, as at a' a'. These arms extend rearward parallel, or nearly so, with the legs of the U portion, then turn inward, as at a'a', and finally approach each other toward a converging point, terminating behind the loop a of the U-shaped central portion, as shown in all the figures of the drawings. These links are united to form a

chain in a manner as shown in Figs. 1 and 2—that is, in pairs, the loops a'a' of a pair of links engaging the loops a of the succeeding pair of 30 links.

The characteristic feature of this design, and that which gives special distinctiveness to the claim therefor, is the ornamental effect produced by the continuous rearward extension of the 35 ends of the U or central bend of the links, so as to lie parallel, or nearly so, with the legs of the central U portion, and the curvature of the extreme ends inward toward a meeting-point to embrace the bend of the central U. 40

What I claim, and desire to secure by Letters Patent, is—

The design for an ornamental chain, consisting of united links, each of which has a central U-bend, bends which return the ends outward 45 and rearward, so as to be parallel, or nearly so, with the legs of the U, and final beads, which turn the ends inward toward a common meeting-point, so as to embrace the central U-bend, substantially as described and shown.

DAVID D. NEVINS.
